UNITED STATES PATENT OFFICE.

ALBERT BROADMEYER, OF HARRISBURG, PENNSYLVANIA, ASSIGNOR TO THE W. O. HICKOK MANUFACTURING COMPANY, OF HARRISBURG, PENNSYLVANIA, A CORPORATION OF PENNSYLVANIA.

STOP MECHANISM FOR SHEET-FEEDING APPARATUS.

Application filed January 19, 1927. Serial No. 162,162.

The present invention relates to means for stopping the feed of paper sheets when an excessive number are simultaneously delivered to the conveying apparatus.

5 In certain aspects, the invention may be considered as an improvement on the apparatus disclosed in my application, Serial No. 747,564, filed Nov. 23, 1924.

The object is to provide a novel form of 10 mechanism, by which the feeding means is made inactive and in which a stop is employed that engages the excessive sheets and holds them against movement.

15 In the accompanying drawings:

Figure 1 is a view in elevation of the preferred embodiment of the invention,

Figure 2 is a perspective view of the same,

Figure 3 is a horizontal sectional view taken on the line 3—3 of Figure 1;

20 Figure 4 is a detail sectional view through a mounting of one of the presser rollers.

In the embodiment disclosed, a portion of a table is illustrated at 5, on which a pile of sheets 6 is placed. It will be understood 25 that any desired type of table-elevating mechanism may be employed. Behind said table is a suitable conveyer, shown at 7, for carrying sheets delivered from the pile 6 to a suitable apparatus for operating on said 30 sheets. Interposed between the table 5 and the conveyor 7 is a transfer roller 8 that constitutes a part of the conveying mechanism.

For the purpose of feeding the sheets successively from the pile 6, any suitable means 35 may be employed. The present embodiment shows a suction roller 9 of the type disclosed in the patent granted to me on May 13, 1924, No. 1,494,303. Suction is created 40 through this roller by means of a conduit 10 leading from a suction pump, and in the conduit is located a relief vent 11. The vent 11 is normally closed by a slide valve 12 carried on a reciprocating bar 13 that is 45 slidably mounted in ways 14 formed upon the side of the conduit 10.

Located above the receiving end of the conveyor 7 is a rock shaft 15, having a longitudinal keyway 16. A collar 17, mounted 50 on the rock shaft 15, is provided with a key 18 engaged in the keyway, so that the collar will rotate with the rock shaft. This collar is provided with oppositely outstanding arms 19 and 20. The arm 19 terminates

55 at its outer end in a vertical sleeve 21, in which is slidably mounted a stem 22. The stem has at its lower end a head 23 that is adapted to move downwardly into contact with the conveyor 7, or with sheets on said conveyor, when the arm 19 swings 60 downwardly. A spring 24 is interposed between the head 23 and sleeve 21, and serves to yieldingly urge the head 23 downwardly. A stop collar 25, fixed to the upper end of 65 the stem 22, and abutting against the upper end of the sleeve 21, serves to limit the downward movement of the head and stem with respect to the sleeve. In order to urge the arm 19 and head 23 downwardly there 70 is secured to the rock shaft 15, an upstanding arm 26 having an offset portion 27, on which is adjustably mounted a weight 28.

Extending over the roller 8 is a supporting bracket 29, and said bracket has pivotally mounted thereon, as indicated at 30, a bell 75 crank bracket, comprising an arm 31 and an arm 32. The arm 31 is interposed between a spring 33 supported on an ear 34 of the bracket 29, and an adjusting screw 35 threaded through an ear 36 on said bracket 80 29. A lock nut 37 serves to secure the screw 35 against accidental movement.

The other arm 32 is provided with an outstanding pivot pin 38, on which is journaled 85 a detent arm 39. The upper end of this arm 39 is offset and overhangs the arm 20, as shown at 40, and through said offset end 40 is threaded a locking screw 41, the lower end of which is adapted to seat in a notch 42, formed in the upper side of the arm 20. 90 The arm 39 extends below the pivot 38 and is provided with a horizontal pin 42^a. Journaled on the pivot 38 alongside the arm 39 is a detector cam 43, the eccentric peripheral edge of which cooperates with the roller 8. 95 This detector 43 has an arcuate slot 44 therein in which the pin 42^a is engaged, the arrangement being such that the pin 42^a is normally at a point between the ends of the slot 44. The pin 42^a has also connected 100 thereto a link 45 that is pivoted, as shown at 46, to the slide bar 13. The usual idler disk 43^a is journaled on the pivot 38 at the rear side of the arm 39.

Under normal conditions, the arm 19 is 105 held in elevated position, so that the head 23 is out of coaction with the conveyor 7 by the screw 41 being engaged in the notch 42.

of the arm 20. The passage of the peripheral edge of the detector 43 is such that one sheet of paper can pass from the pile 6 to the conveyor 7 over the roller 8 and beneath the detector 43 without engaging said peripheral edge. This can be accomplished by adjusting the screw 35 to elevate or depress the pivot 38 on which the detector is carried. If, however, two or more sheets 10 should simultaneously pass over the roller 8, the detector will be engaged by the upper sheet and caused to be turned thereby. This initial movement is free so that it will gain momentum, but when the end of the slot 44 strikes the pin 42^a, the upper end of the arm 39 will be swung rearwardly, thus elevating the screw 41 out of the notch 42, releasing the rock shaft 15 and permitting the head 23 to drop either onto the conveyor 7 or on 20 the excessive sheets carried thereby. These sheets are therefore stopped. At the same time, the forward movement of the pin 42^a by the detector 43 causes the forward movement of the link 44, arm 13 and closure 25 valve 12. Thus the vent 11 is opened and suction through the conduit 10 is relieved by said vent. The result is that the suction roller 9 is made inoperative.

Cooperating with the roller 8 are presser 30 rollers 47. These rollers are journaled on the free ends of arms 48 that are rotatably supported on the rock shaft 15. As shown, the journaled ends of the arms 48 are bifurcated as shown at 49, and in said bifurcations are placed collars 50 secured to the shaft 15 by set screws 51. The collars have pins 52 that are adapted to abut against the undersides of the arms.

This structure, it will be noted therefore, 40 permits the rollers 47 to coact with the shaft 8, and to have limited play. When, however, the rock shaft 15 turns to permit the head 23 to drop, the arms 48 are swung upwardly by reason of the pins 52 striking 45 said arms and thus the rollers 47 are elevated, relieving the sheets from being pressed upon the roller 8 and thus permitting the stopping of said sheets without stopping the roller 8.

50 From the foregoing, it is thought that the construction, operation and many advantages of the herein described invention will be apparent to those skilled in the art, without further description, and it will be understood that various changes in the size, shape, proportion and minor details of construction may be resorted to without departing from the spirit or sacrificing any of the advantages of the invention.

60 What I claim is:

1. The combination with sheet conveying means, of a sheet stop movable from an inactive position to a position to engage and hold sheets carried by the conveying means, 65 a detent detachably engaging the stop for

holding said stop in its inactive position, a sheet-engaging detector operated by an excessive number of sheets carried by the conveying means, and means for operating the detent on the operation of the detector, to 70 release the stop.

2. The combination with sheet conveying means, of a sheet stop movable from an inactive position to a position to engage and hold sheets carried by the conveying means, 75 a detent detachably engaging the stop for holding said stop in its inactive position, a sheet-engaging detector operated by an excessive number of sheets carried by the conveying means and having a slot, and a device for operating the detent to release the stop, said device having a portion located 80 in the slot and adapted to be engaged and operated by the detector.

3. The combination with sheet conveying 85 means, of a sheet stop having a pivotal mounting and adapted to engage and hold sheets carried by the conveying means, a swinging detent that engages the stop to hold it in its inactive position, an actuating 90 arm connected to the detent and having a pin, and an oscillatory detector having a slot in which the pin is engaged.

4. The combination with sheet conveying 95 means, of a rock shaft thereover, a swinging stop lever carried by the rock shaft and extending on opposite sides of the same, a sheet stop finger yieldingly mounted on one arm, a pivot, a second lever on the pivot having an arm provided with a detent engaging the other arm of the stop lever, the other arm of the second lever having a pin, and a detector mounted on said pivot and having a slot in which the pin is engaged.

5. The combination with sheet conveying 105 means, of a rock shaft thereover, a swinging stop lever carried by the rock shaft and extending on opposite sides of the same, a sheet stop finger yieldingly mounted on one arm, a swinging pivot mounting, means for 110 adjusting said mounting, a pivot carried by the mounting, a second lever on the pivot having an arm provided with a detent engaging the other arm of the stop lever to that carrying the stop finger, the other arm 115 of the second lever having a pin, and a detector mounted on said pivot and having a slot in which the pin is engaged.

6. The combination with sheet conveying 120 means including a roller, of a pressure roller coacting with said sheet conveying roller and movable toward and from the same, a sheet stop movable into a position to engage and hold sheets carried by the conveyor, and means controlled by the pressure 125 of an excessive number of sheets for causing the stop to move to its active position and the pressure roller to move to its inactive position.

7. The combination with sheet conveying 130

means including a roller, of a pressure roller coacting with said sheet conveying roller and movable toward and from the same, a sheet stop movable into a position to engage and hold sheets carried by the conveyor, a detent for holding the stop out of such position and holding the pressure roller in coaction with the conveyor roller, and means operated by a plurality of sheets for moving the detent to permit the stop to move to its active position and the pressure roller to move to its inactive position.

8. The combination with sheet conveying means including a roller, of a rock shaft above the conveying means, a pressure roller having a mounting on the shaft and normally cooperating with the conveyor roller, a sheet stop also having a mounting on the rock shaft and normally out of the path of the sheets moved by the conveyor, and means including a detector operated by an excessive number of sheets for moving the rock shaft to move the pressure roller out of coaction with the conveyor roller and move the stop into a position to engage the excessive sheets.

9. The combination with sheet conveying means including a roller, of a rock shaft above the conveying means, an arm carried by the rock shaft and projecting beyond one side of the same, a pressure roller on the arm and normally cooperating with the conveyor roller but movable away from the same on the rotation of the rock shaft, another arm carried by the rock shaft and projecting from the opposite side thereof, a sheet stop carried by the latter arm and movable toward the conveying means when the pressure roller is moved away from the conveyor roller, a detent for holding the rock shaft with the stop elevated and the roller lowered, and a device operated by an excessive number of sheets and operating the detent.

45 10. The combination with sheet conveying means including a roller, of a rock shaft above the conveying means, an arm carried by the rock shaft and rotatable therewith, said arm projecting beyond one side of the rock shaft, a pressure roller on the arm and normally cooperating with the conveyor

means including a roller, of a pressure roller coacting with said sheet conveying roller and movable toward and from the same, a sheet stop carried by the latter arm and held elevated when the pressure roller is in cooperation with the conveyor roller, a swinging detent that holds the rock shaft against movement and having an arm, and a swinging sheet detector having a slot in which a portion of the arm is engaged.

55 11. The combination with a suction feeding device, and a suction conduit having communication therewith, said conduit having a relief port, of a movable closure for the relief port, a swinging sheet detector having a slot, a link connected to the closure, and a pin connected to the link and engaged in the slot of the detector, said pin being normally spaced from the end of the slot that engages the pin when the detector is swung.

60 12. The combination with a conveyor including a transfer roller and a suction roller, of a rock shaft, an arm fixed to the rock shaft, a sheet stop finger carried by the arm, a pressure roller mounted on the shaft and cooperating with the conveyor roller, a swinging support, means for holding the support in different positions, a detent journaled on the support and operating to hold the rock shaft against turning, a suction conduit for the suction roller having a vent, a movable closure for the vent, a connection between the closure and the detent, a swinging detector journaled on the support and having a slot, and a pin carried by the detent and engaged in the slot.

65 13. In sheet feeding means, a movable sheet carrying member, of a roller normally coacting with the member and movable to a position out of coaction therewith, an operating device for moving the roller out of such coacting relation, a detent detachably engaging the operating device to hold it against action, and a device operated by an excessive number of sheets for moving the detent to release the operating device and permit it to effect the interruption of the feeding operation.

70 In testimony whereof, I affix my signature.

ALBERT BROADMEYER.
